UNITED STATES PATENT OFFICE.

NIELS JONAS NIELSEN, OF AARHUS, DENMARK.

APPARATUS FOR CLOSING HERMETICAL BOXES OR THE LIKE.

Application filed November 27, 1922. Serial No. 603,721.

To all whom it may concern:

Be it known that I, NIELS JONAS NIELSEN, of 15 Frederiksgade, Aarhus, in the Kingdom of Denmark, have invented certain new and useful Improvements in or Relating to 5 Apparatus for Closing Hermetical Boxes or the like, of which the following is a full, clear, and exact description.

My present invention concerns the closing 10 of hermetical boxes or the like and has for its object to perform the closing in such a way that each box at the closing moment, becomes evacuated of air and hence the conserve in the box is protected against 15 mould.

My invention is by way of an example diagrammatically shown on the drawing.

Figs. 1 and 2 show a form of an apparatus in a vertical section and a plane view 20 respectively. To be more explicit Fig. 1 shows the evacuated system developed. Fig. 3 shows a vertical section rectangular to that of Fig. 1.

The apparatus comprises a cylinder 7 enclosing a turnable table. This table consists of an upper plate 8 and a lower plate 80 with even situated openings, forming a number of places for boxes 9 or the like. Above and below the cylinder 7 and somewhat overlapping it there are two other cylinders 10 and 11 respectively each enclosing a turnable table 12 and 13, respectively, with a corresponding number of boxplaces. The cylinders 10 and 11 communicate with 30 the cylinder 7 through openings permitting the cylinder 7 to fall through. The table 8, 80 passes close to these openings. The shafts of the three tables have suitable members 14, 15 and 16, respectively, permitting them to be turned by cams or the like 17, 18 and 40 19 respectively on a common shaft 20 in such a way that the tables by a revolution or a certain part of a revolution of the shaft 20, are turned a boxplace forward causing 45 a box to fall from the cylinder 10 down on an empty boxplace in the table 8, 80 and a closed box to fall from this table down in the cylinder 11. The cylinder 10 communicates with a transport belt or the like 21 50 for the filled boxes, which are to be closed, the cylinder 11 communicates with a transport belt or the like 22 for the closed boxes, and the cylinder 7 is by a conduit 23 connected with a suitable vacuum source.

Speaking for instance about boxes for sweetened condensed milk, filled into the

box through a small aperture, I prefer to close this aperture by the solder button described in my copending application, Serial No. 603,722, filed November 27, 1922. Before the closing the solder button is fixed on the box near the aperture, e. g. in an oblique position, being soldered on a point of its circumference or otherwise. The solder button will in that way stand ajar. 60 The full boxes with the solder buttons ajar are one by one delivered from the belt 21 to an opening in the top of the cylinder 10. This cylinder, acting as an air sluice before the evacuated cylinder 7, has a lower air 65 pressure than that of the atmosphere and the air in the box will therefore be somewhat thinned. As the boxes one by one arrive at the above mentioned opening communicating with the cylinder 7, they fall down 70 on an empty place on the table 8, 80 where they are exposed to the desired degree of vacuum, and with the corresponding degree of evacuation they arrive at the boxplace 90. Here they are closed e. g. by the mechanism 80 shown in Fig. 3.

This mechanism consists of a hollow soldering bolt 24, electrically heated and coacting with a central pressure pin 25. The soldering bolt is periodically lifted by 85 levers 26 and rods 27, actuated by a cam 28 on the shaft 20. Further, the soldering bolt is rotated by means of cog wheels or friction discs 29 and 30, the last mentioned of which is turned from the shaft 20 by 90 means of worm and worm wheel or the like.

Directly before each turning of the table 8, 80 the soldering bolt is lifted so as to enable the box just closed to leave, and a 95 new box with the solder button ajar to enter the soldering position. Directly after the turning of the table the soldering bolt is lowered; owing to its heat the solder button firstly falls down on the aperture and secondly owing to the rotation of the soldering bolt the solder and flux are quickly and evenly distributed.

After the buttons have been soldered the boxes pass to the above mentioned opening, 105 communicating with the cylinder 11, and fall down in this cylinder which also acts as an air sluice. At last they fall down on the belt or the like 22.

Preferably the belts 21 and 22 carry the 110 boxes along only on account of the friction. The belts are constantly moved, and when

for instance a box is pushed into the apparatus, the belt 21 moves all the boxes standing on it, but when the box has reached its place in the apparatus, it stops the following 5 boxes on the still moving belt until it is turned away, thus giving room for another box.

I claim:

1. In apparatus for closing hermetically sealed boxes, the combination with a vacuum chamber having a rotatable disk adapted to support a box while the latter is being sealed, of air sluices situated above and below the said vacuum chamber and having 10 rotatable disks mounted therein, the disk in one of said sluices being adapted to drop a box onto the disk of the vacuum chamber, and the disk in the other one of said air sluices being adapted to receive a sealed box 15 dropped from the rotatable disk of the vacuum chamber, and means for rotating said 20 disks in timed relation.
2. An apparatus as claimed in claim 1 wherein the air sluices are in communication with the vacuum chamber, so that the 25 air sluices are also under reduced pressure.
3. An apparatus as claimed in claim 1 wherein the means for rotating the disks includes cams mounted on a common shaft, 30 said cams being adapted to intermittently move the disks forward.
4. An apparatus for sealing receptacles

under vacuum, comprising a vacuum chamber, a turn table located in the vacuum chamber and provided with means for engaging and carrying receptacles, means for intermittently moving the table step by step, sealing means associated with the vacuum chamber for sealing receptacles as they pass through the latter, a feeding sluice arranged above the vacuum chamber and communicating with the latter at one point, a turn table arranged in the feeding sluice and adapted to move the receptacles and drop the same on to the turn table of the vacuum chamber, means for intermittently rotating the last mentioned turn table, and a discharge sluice way arranged below the vacuum chamber and having a turn table adapted to receive and carry receptacles 45 dropped in the vacuum chamber, and means for moving the last mentioned turn table step by step.

5. An apparatus as claimed in claim 4 in which the receptacle sealing means includes 50 a bolt movable toward and away from the vacuum chamber, means for heating said bolt, means for rotating the bolt, and means for intermittently raising and lowering said bolt.

In witness whereof I subscribe my signature.

NIELS JONAS NIELSEN.
